United States Patent Office.

JOHN McLAUGHLIN, OF BROOKLYN, NEW YORK.

Letters Patent No. 66,374, dated July 2, 1867.

IMPROVEMENT IN REGISTERS.

The Schedule referred to in these Letters Patent and making part of the same.

TO ALL WHOM IT MAY CONCERN:

Be it known that I, JOHN McLAUGHLIN, of Brooklyn, in the county of Kings, and State of New York, have invented a new and useful "Improvement in Registers;" and that the following description, taken in connection with the accompanying drawings hereinafter referred to, forms a full and exact specification of the same, wherein I have set forth the nature and principles of my said improvements, by which my invention may be distinguished from all others of a similar class, together with such parts as I claim, and desire to have secured to me by Letters Patent.

The present invention relates to hot-air registers more particularly, although it can be applied to other registers, and the invention consists in the use of a sheet or sheets of wire gauze or netting within the body of the registers and across the plane of its openings for the purpose of preventing papers or other articles dropping or passing through the register to the fire below, while no hindrance is given to the heated air passing through the register. In the accompanying plate of drawings my improvement in registers is illustrated—

Figure 1 being a central longitudinal vertical section through the register, and

Figure 2 a plan or top view of the wire gauze or sheet netting.

A, in the drawings, represents a register made of any of the ordinary constructions or forms. B, a sheet of wire gauze or netting, secured in register A across the same, and just back of its openings C, this netting acting as a stop to the passage of paper, etc., through the register, while at the same time the passage of heated air is not in the least degree interfered with.

Having thus described my invention, I claim as new, and desire to secure by Letters Patent—

The screen B to the register, substantially as and for the purpose described.

The above specification of my invention signed by me this 12th day of March, 1867.

JOHN McLAUGHLIN.
